(57) **CLAIM**

The ornamental design for a headlight daytime running light arrangement, as shown and described.

DESCRIPTION

FIG. 1 is a front left elevated perspective view of a headlight daytime running light arrangement, showing our new design.

FIG. 2 is a front left perspective view thereof.

FIG. 3 is a front view thereof.

FIG. 4 is a left side view thereof.

FIG. 5 is a top view thereof.

FIG. 6 is another front view of the headlight daytime running light arrangement shown in FIGS. 1-5, with the headlight daytime running light arrangement shown on a vehicle, and the rest of the vehicle shown in de-emphasized and half-tone portions so as to illustrate environmental structure, which portions form no part of the claimed design. More particularly, in FIG. 6, the headlight daytime running light arrangement is shown within the broken line, and the elements shown outside the broken line form no part of the claimed design, but are instead included to show environmental aspects thereof; and,

FIG. 7 is a variation on the embodiment shown in FIG. 6, but showing the headlight daytime running light arrangement on both sides of the vehicle. Again, the vehicle is shown in de-emphasized and half-tone portions so as to illustrate environmental structure, which portions form no part of the claimed design. More particularly, in FIG. 7, the head light daytime running light arrangement is shown within the broken lines, and the elements shown outside the broken lines form no part of the claimed design, but are instead included to show environmental aspects thereof.

A second embodiment includes the mirror image of the headlight daytime running light arrangement shown in FIGS. 1-5.
